CLAIM

The ornamental design for a fastener for attaching wire harness, as shown and described.

DESCRIPTION

FIG. 1 is a perspective view of a fastener for attaching wire harness showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The break away portions of the harness shown in broken lines are for illustrative purposes only and do not form part of the claimed design.
